(57) **CLAIM**

The ornamental design for a faucet, as shown and described.

DESCRIPTION

FIG. 1 is a perspective view of a faucet showing my new design.

FIG. 2 is another perspective view of a faucet.

FIG. 3 is a front view of a faucet.

FIG. 4 is a rear view of a faucet.

FIG. 5 is a left side view of a faucet.

FIG. 6 is a right side view of a faucet.

FIG. 7 is a top view of a faucet; and,

FIG. 8 is a bottom view of a faucet.

Any shading is not features of the design but is utilized to illustrate the surface contours of the faucet design in the drawings.

The broken lines illustrate portions of the faucet that form no part of the claimed design.
